UNITED STATES PATENT OFFICE.

LUDWIG HONIGMANN, OF BAD TOLZ, AND FRIEDRICH BARTLING, OF MUNICH,
GERMANY.

RING OVEN WITH REVOLVING HEARTH.

Application filed June 2, 1926, Serial No. 113,286, and in Germany June 3, 1925.

Our Patent No. 1,634,027, issued June 28, 1927, relates to a ring oven with revolving hearth for the treatment by heat of pulverulent granular or like material which at the charging point is applied in the form of a thin layer to the revolving hearth while the forward radial edge of the charging box wipes off the excess material from the hearth. The product treated by heat is then sucked away at the delivery point together with the gases from the oven chamber and these gases are then conveyed after the separation of the pulverulent products back into the oven.

The object of this invention is a particularly useful construction of this oven the aim being first of all to enable at the outset only a small part of the oven gases to be split off as delivery means and to be conveyed in a separate circulating current 20 through the delivery point and the dust separator.

In order to attain this, use is made according to this invention of a discharge device wherein a closed pipe conduit, built into 25 which is a dust separator and a circulating pump, is provided with a jet-like interruption which is directly situated above the delivery point of the ring oven so that the gas current carries off the oven material to be carried out.

In order to safeguard the separation from the bulk of the oven gases, there is provided above the discharge point, a substantially closed box beneath the open underside of 35 which the ring hearth is displaced, and in which is arranged the jet nozzle. The suction pipe of the circular current conduit terminates by preference in a closed head, the lateral wall of which, situated in the direction of the advancing ring, is provided with sieve-like perforations opposite to which is arranged the nozzle opening of the pressure pipe. This has for its result that a jet of 40 working gas is caused to pass directly over the discharge point of the hearth which jet, in the manner of a jet pump, carries away the dust-like material located beneath. Due to the particular arrangement of the jet nozzle a direct blowing on and consequential 45 whirling of the material on the hearth is counteracted. The discharge head may be closed below by a solid bottom or may be open and operate so closely above the revolving hearth that the latter closes the

head relatively tightly and thus substantially replaces the bottom. The head of the suction pipe may, according to this invention, be connected to the suction conduit by flexible means for example a metal hose or a flexible tube. It glides positively under the influence, for example, of its own weight or of a spring on guide ways of the hearth, being prevented from being carried along by appropriate means. The last mentioned arrangement may usefully be applied also to the charging point where, according to the previously mentioned patent, the lower edge of the charging hopper wipes over protruding ribs, ledges or like projection on the hearth surface between which the material is introduced in appropriate grooves or like cavities. The object of this arrangement is a wiping off of the charged material by the charging hopper itself in order to counteract accumulations of the material on the hearth 75 and to distribute it in a thin layer.

The use of this arrangement for regulating the layer presents difficulties in so far as it presupposes an accurately uniform circulation of the hearth in a horizontal plane 80 which of course is attainable only within certain limits and moreover because the considerable heat of the oven hearth and other parts thereof are liable to change their dimensions. For this reason the regulation of 85 the thickness of the layer by means of this device can be attained only in a more or less general way. In cases in which the materially finer regulation is desired the requisite aid is to be created by the present invention. The device forming the subject of the aforementioned patent renders it more particularly impossible to charge different thicknesses and this again is to be rendered possible by this invention, the idea being 90 that, for the perfection of the charging device serving as a layer regulator, it should be possible to enable an automatic precise adjustment of the charging box relatively to the hearth also in such cases in which the 95 hearth does not rotate precisely in a horizontal plane or is subject to variations during the working. Again an arbitrary regulation of the thickness of the layer should be possible, taking into account various 100 working conditions, materials or the like.

Accordingly a further characteristic feature of the invention resides in the coupling,

at the charging point, of the oven of the charging box with the stationary charging pipe by flexible means and to cause it to wipe over the guide ways of the hearth by positive pressure while preventing it from being carried along with the rotating hearth by appropriate arrangement. The weight of the charging box, which per se is not prevented from an automatic adjustment by any rigid connection, permits the box to wipe on the guide ways of the hearth even if the latter deviates from its horizontal rotary plane.

In order, in addition, to enable the thickness of the layer to be arbitrarily varied, the charging box according to this invention is provided with a vertically adjustable slide operating between the guide ways.

In a preferable construction the arrangement is to be such that the surface of the ring hearth is provided with two ring shaped marginal ledges over which the edges of the charging box are caused to wipe and between which the surface of the ring hearth is provided with teeth, roughenings or the like for the engagement of the material charged thereon. Instead of depressing the charging box on to the hearth by its own weight use may of course be made also of any other device, for example, of springs.

A constructional form of the invention is illustrated by way of example in the accompanying drawings in which:—

Fig. 1 represents a section of the ring hearth in the direction of its advance at the discharge point,

Fig. 1^a is a fragmentary top plan, on a reduced scale, of the construction shown in Fig. 1, with the addition of certain elements to complete the circulating conduit,

Fig. 2 is a sectional view at the charging point and

Fig. 3 is a radial section of the oven taken through the charging point.

The oven shown in this constructional form is provided in known manner with a ring shaped flue *a* covered on top and open at the bottom. The lower opening is bridged by the annular revolving hearth *a*¹ which moves in the direction of the arrow *b* and is outwardly packed for instance by means of sand troughs or water charged cooling troughs *n*, *o* (Fig. 3). The hearth *a*¹ is maintained in movement by means of a gear *p*.

According to the invention the upper surface of the hearth is provided with projecting guide ways such as marginal ledges *r* between which the surface of the hearth is appropriately cavitated. By preference the surface of the hearth is provided with teeth or is otherwise roughened for a ready engagement of the material thereon.

Arranged at the discharge point A in the oven chamber is a box *c* which is closed on all sides except at the bottom. The open

bottom is however obturated by the revolving hearth *a*¹ moving beneath the same. From above there extends a pressure pipe *d* and a suction pipe *e* which are connected, to form a closed circulating conduit, as shown in Fig. 1^a, in which a circulating gas current is maintained by a blower *r* and a dust separator *s* of any suitable construction. The suction pipe *e* carries a hollow head *f* of say square shape which has a relatively great weight and is coupled with the suction pipe *e* by flexible means, for instance a metal hose *g*. The heavy head *f* wipes, with its lower closed or open end, over the guide ways on the revolving hearth *a*¹ thus adapting itself to any deviations of the hearth from the precisely horizontal position. The head is prevented by any appropriate means such as a transverse bar *f*¹ from being carried along with the hearth. The face *h* of the head situated in the direction of the hearth advance is perforated in a sieve-like manner. The pressure pipe *d* has its lower open end bent so as to blow its gas jet directly against the perforated wall *h* and through same. When the pump is started it sucks from the pipe *e* a certain amount of working gas which thereafter circulates continually through the circulating conduit. The gas flows from the pressure pipe *d*, the terminal *d*¹ of which may be constricted, in the form of a sharp edge and after crossing the space between the two pipes penetrates through the perforated face *h* whence it is sucked over to the dust separator. In this action the pulverulent or granular layer of material is completely sucked away from the hearth by the jet action.

The charging device at the charging point B comprises a charging box *i* of sufficient weight, the edges of which wipe on the marginal ledges *r* of the hearth. It is prevented from being carried along by the hearth by transverse stop bars *i*¹ or the like. The box is connected by a flexible link, for example a flexible pipe *g*¹ to the charging pipe *l* proper, which is stationary. Arranged at one of the broad sides of the charging hopper is a vertically displaceable slide *m* which projects beyond the lower edge of the hopper and is so shaped as to enter between the guide ledges *r*. By vertical adjustment of the slide *m* the thickness of the material charged may be regulated at will.

We claim—

1. In a ring over for the treatment by heat of pulverulent, granular or like material in which the material at the charging point is charged in the form of a thin uniform layer and at the discharge point sucked away with the oven gases, a revolving hearth, a conduit through which a portion of the oven gases are diverted past the discharge point to act as a discharging means, said conduit having a jet nozzle therein ar- 130

ranged immediately above said discharge point, a dust separator in said conduit, and a pump also in said conduit.

2. In a ring oven for the treatment by heat of pulverulent, granular or like material in which the material at the charging point is charged in the form of a thin uniform layer and at the discharge point sucked away with the oven gases, a revolving hearth, 10 a conduit through which a portion of the oven gases are diverted past the discharge point to act as a discharging means, said conduit having a jet nozzle therein arranged immediately above said discharge point, a 15 dust separator in said conduit, a pump also in said conduit, and a closed box above said discharge point having an open underside adjacent said hearth and in which said jet nozzle is located.
- 20 3. In a ring oven for the treatment by heat of pulverulent, granular or like material in which the material at the charging point is charged in the form of a thin uniform layer and at the discharge point sucked away with the oven gases, a revolving hearth, a conduit through which a portion of the oven gases are diverted past the discharge point to act as a discharging means, said conduit including a pressure pipe having a jet nozzle disposed above said discharge point, and also including a suction pipe having a head provided with a perforated side arranged opposite said jet nozzle and facing in the direction of revolution of said hearth, and a 25 dust separator in said conduit.

4. In a ring oven for the treatment by heat of pulverulent, granular or like material in which the material at the charging point is charged in the form of a thin uniform layer and at the discharge point sucked away with the oven gases, a revolving hearth, a conduit through which a portion of the oven gases are diverted past the discharge point to act as a discharging means, said conduit including a pressure pipe having a jet nozzle disposed above said discharge point, and also including a suction pipe having a head provided with a perforated side arranged opposite said jet nozzle and facing 40 in the direction of revolution of said hearth, flexible means coupling said head with the remainder of the suction pipe so that said head is caused to wipe over the adjacent surface of said hearth, and means to prevent movement of said head with said hearth.

5. In a ring oven for the treatment by heat of pulverulent, granular or like material in which the material at the charging point is charged in the form of a thin uniform layer and at the discharge point sucked away with the oven gases, a revolving hearth, a conduit through which a portion of the oven gases are diverted past the dis-

charge point to act as a discharging means, said conduit including a pressure pipe having a jet nozzle disposed above said discharge point, and also including a suction pipe having a head provided with a perforated side arranged opposite said jet nozzle and facing in the direction of revolution of said hearth, flexible means coupling said head with the remainder of the suction pipe so that said head is caused to wipe over the adjacent surface of said hearth, means to prevent movement of said head with said hearth, a charging pipe, a charging hopper at said charging point wiping over the surface of said hearth as the latter is revolved, flexible means connecting said charging pipe with said charging hopper to permit the latter to engage said hearth, and means to prevent said charging hopper being carried along with said hearth.

6. In a ring oven for the treatment by heat of pulverulent, granular or like material in which the material at the charging point is charged in the form of a thin uniform layer and at the discharge point sucked away with the oven gases, a revolving hearth, a conduit through which a portion of the oven gases are diverted past the discharge point to act as a discharging means, said conduit including a pressure pipe having a jet nozzle disposed above said discharge point, and also including a suction pipe having a head provided with a perforated side arranged opposite said jet nozzle and facing in the direction of revolution of said hearth, flexible means coupling said head with the remainder of the suction pipe so that said head is caused to wipe over the adjacent surface of said hearth, means to prevent movement of said head with said hearth, a charging pipe, a charging hopper at said charging point wiping over the surface of said hearth as the latter is revolved, flexible means connecting said charging pipe with said charging hopper to permit the latter to engage said hearth, means to prevent said charging hopper being carried along with said hearth, and a vertically adjustable slide for said charging hopper adapted to extend between the guideways of said hearth.

7. In a ring oven as claimed in claim 5, wherein a surface of the hearth is provided with annular marginal projections for the wiping over of the edges of the charging hopper and between which the surface of the hearth is roughened for engagement of the material to be carried thereon.

In testimony whereof we have signed our names to this specification.
